UNITED STATES PATENT OFFICE.

MAJOR HILL, OF CHICAGO, ILLINOIS, ASSIGNOR TO E. L. MASURE COMPANY, OF CHICAGO, ILLINOIS, A CORPORATION OF ILLINOIS.

DESIGN FOR UPHOLSTERY AND DRAPERY EDGING.

Application filed July 9, 1925. Serial No. 14,030. Term of patent 7 years.

To all whom it may concern:

Be it known that I, MAJOR HILL, a citizen of the United States, residing at Chicago, Cook County, Illinois, have invented a new, original, and ornamental Design for Upholstery and Drapery Edging, of which the following is a specification, reference being had to the accompanying drawing, forming part thereof.

The figure is a face view of a piece of edging showing my new design.

I claim:

The ornamental design for upholstery and drapery edging as shown.

MAJOR HILL.
